[57] **CLAIM**

The design for a toilet trainer for cats, as shown and described.

DESCRIPTION

FIG. 1 is a top plan view of a toilet trainer for cats showing my new design;

FIG. 2 is a front elevational view thereof;

FIG. 3 is a bottom plan view thereof;

FIG. 4 is a side elevational view thereof;

FIG. 5 is a cross sectional view taken on line 5—5 of FIG. 1; and

FIG. 6 is a reduced scale top plan view thereof.

The broken line representation of a water closet in FIG. 6 is for purposes of illustration only.
